ELASTIC THREAD

Francis J. Kennedy, Needham, Mass.

Application September 28, 1934, Serial No. 745,911

4 Claims. (Cl. 117—21)

This invention relates to elastic thread of the type useful for the manufacture of elastic surgical bands or other similar fabrics. The thread embodying the present invention is a multi-strand twisted thread, each strand being characterized by a continuous rubber core of one or more filaments having a single or multiple helical wrapping of fibrous yarns.

In the manufacture of elastic thread, a core of one or more rubber filaments is fed longitudinally in stretched condition while a spool of fibrous yarn is carried around the core so as to wrap the same with helical turns of yarn. If the wrapped core is then released, it has a strong tendency to kink and twist. This tendency has made it difficult to handle such elastic thread in machines for knitting or weaving fabrics. To overcome this kinking tendency, a second wrapping of textile yarns is customarily made on the rubber core by passing a second spool of yarn about the core in the opposite direction so that the thread is thus provided with superimposed wrappings in opposite directions. This greatly reduces but does not altogether remove the tendency to kink. According to the present invention, instead of attempting to offset or compensate for the natural tendency on the part of the single-wrapped rubber core to twist and kink, I put this tendency to use by laying such a strand along side of other similar strands and twisting these strands together to form a multi-strand elastic thread. Such a strand can be used without trouble or difficulty, as, for example, in a machine for knitting or weaving elastic fabrics.

For a more complete understanding of the invention, reference may be had to the description thereof which follows, and to the drawing of which

Figure 1 shows in elevation a piece of rubber core with a single layer of yarns wound thereon.

Figure 2 shows in elevation a piece of two-strand thread made by twisting together two strands similar to that shown in Figure 1.

Figure 3 shows an elastic thread made of four strands twisted together.

Figure 4 shows a modified form of the invention.

Figure 5 shows a large cord made of a plurality of multiple-strand threads.

The invention may be characterized in one of its aspects by a multi-strand thread having two or more strands 10 twisted together as illustrated in Figures 2 and 3, each strand having a core 11 of one or more filaments of untwisted resilient material, such, for example, as soft rubber. On

each core 11 is wound a single layer of fibrous yarns 12. While the core 11 may, if desired, be wrapped with a single yarn 12, it is preferable for economy of time to wrap several threads on the core simultaneously, the threads being fed in 5 side-by-side relation so that they form a single layer covering the core with a fibrous sheath having a uniform thickness equal to the diameter of one of the yarns. As the core is stretched and under tension when being wrapped with the 10 yarns 12, the wrapped core, if released, has a tendency to twist and kink. According to the present invention, this tendency to twist is utilized by bringing together two or more strands 10 each consisting of a resilient core 11 wrapped 15 in the same direction with textile yarns 12 as described. These strands are then twisted together to form a multi-strand thread such as is illustrated in Figure 2 or Figure 3. The strands are twisted together in a direction opposite to the 20 direction of wrapping of the yarns 12 so that the tendency of each wrapped strand to twist serves to retain the twist of the several strands in the thread. The twisting of the several strands together may conveniently follow immediately upon 25 the wrapping of the individual strands with fibrous yarns. Thus the twisting tendency of the individual strands is utilized before the strands have had an opportunity to form undesirable kinks.

While the threads of two or four strands are shown, by way of illustration, in Figures 2 and 3 of the drawing, the invention is not limited to any particular number of such strands.

Figure 4 illustrates a modified form of multi-strand thread, each strand 15 having a rubber core 16 and two wrappings 17 and 18 of yarn. If, as shown, these wrappings are wound in opposite directions, the strands will have little tendency to twist or kink. Hence, after the cores 40 16 are wrapped, I twist the wrapped strands 15 before laying them together to form the thread.

As shown in Figure 5, I may make a heavy elastic cord 20 by twisting a suitable number of multi-strand threads such as are illustrated in 45 Figures 2, 3 or 4, and then twisting together these twisted threads.

It is evident that various modifications and changes may be made in the specific embodiments of the invention herein shown and described, 50 without departing from the spirit or scope of the invention as defined by the following claims.

I claim:

1. A method of making twisted thread, which comprises forming a plurality of strands by wrap- 55

ping yarns helically and in the same direction around a plurality of untwisted cores of soft resilient material, and twisting said strands together in the opposite direction.

2. A method of making twisted thread, which comprises forming a plurality of strands by wrapping yarns helically and in the same direction on a plurality of stretched rubber filaments whereby each strand acquires a tendency to twist in the opposite direction, bringing the strands together, and permitting said tendency of the strands to twist them together.

10 3. A twisted elastic thread comprising a plurality of strands which have been doubled without preliminary twist, each said strand consisting of a substantially twist-free core of soft resilient

material with a covering of yarn wrapped helically thereon in one direction only whereby a tendency to twist is imparted to each strand, said tendency being neutralized by doubling in a direction opposite to the direction of wrapping on the 5 cores.

15 4. A twisted elastic thread comprising a plurality of strands which have been doubled without preliminary twist, each said strand consisting of a substantially twist-free rubber core with 10 a covering of yarn wrapped helically thereon in one direction only whereby a tendency to twist is imparted to each strand, said tendency being neutralized by doubling in a direction opposite to the direction of wrapping on the cores. 15

FRANCIS J. KENNEDY.
